(57) **CLAIM**

The ornamental design for a display screen with transitional graphical user interface, as shown and described.

DESCRIPTION

FIG. 1 is a first view of a display screen with transitional graphical user interface showing our new design;

FIG. 2 is a second view thereof;

FIG. 3 is a third view thereof; and,

FIG. 4 is a fourth view thereof.

The broken lines in the drawings illustrate portions of the display screen and transitional graphical user interface that form no part of the claimed design.

1 Claim, 4 Drawing Sheets
